UNITED STATES PATENT OFFICE.

LAURITZ W. ANDERSEN, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

COMBINED SOCKET-COVER AND SHADE-HOLDER FOR ELECTRIC-LIGHT DEVICES.

1,037,101.

Specification of Letters Patent. Patented Aug. 27, 1913.

Application filed April 26, 1912. Serial No. 693,307.

To all whom it may concern:

Be it known that I, LAURITZ W. ANDERSEN, a citizen of the United States, residing at Waterbury, in the county of New Haven and State of Connecticut, have invented a certain new and useful Improvement in Combined Socket-Covers and Shade-Holders for Electric-Light Devices, of which the following is a specification.

10 Heretofore in electric lighting devices, it has been usual to connect a shade for an electric lamp to a socket by a shade ring and a plurality of spaced attaching screws. These latter are very liable to cause the 15 shade to crack under influences of heat and expansion, and the shade ring is very liable to become bent, hence it is difficult to maintain the shade concentric with the lamp, and the object of my invention is to overcome 20 these objections.

In carrying out my invention, I provide a substantially conoidal cover of sheet metal adapted to receive and set over a keyless lamp socket, and the smaller end of this 25 cover is apertured for the pipe of a chandelier, bracket or pendant, or for the electric conductors alone. The larger end of the cover is formed with a circular edge and with a threaded collar secured therein. This 30 collar receives a threaded sleeve which sets within the rim of a shade or the glassware, while the circular edge of the cover comes outside the said rim, and thus the shade or 35 glassware is held in position with an even all-around bearing of an adjustable character.

In the drawing, Figures 1 and 2 are elevations, illustrating the use of the device of my invention. Fig. 3 is a vertical section, through the device of my invention and of about full size, showing a socket and lamp in position, and Fig. 4 is a detached section showing a detail of modified form.

Similar letters and numerals of reference 45 indicate similar parts in all the figures.

a represents the socket cover of conoidal configuration apertured at the small end and provided with an edge *a*¹ of circular form in cross section. These parts are 50 integral and the circular edge may be, and preferably is, ornamented in any desired manner.

b represents a collar fitting within the larger end of the conoidal cover and pro-

vided with a flange *b*¹, by which the said 55 collar is secured by solder or rivets, or both, to the socket cover.

I have shown rivets at 2. I also provide a threaded sleeve *c* having a flange *c*¹.

d represents the lamp socket, which in 60 this particular device is keyless.

*d*¹ represents an incandescent electric lamp.

In Fig. 1, *e* represents a bracket, to which the device of my invention may be connected, while in Fig. 2, *f* represents electric conductors from which, and the socket connected therewith, the socket cover and shade *h* are suspended.

Fig. 1 indicates that the device of my invention may be connected to a fixture, that is to a bracket, electrolier or other electric fixture, while Fig. 2 represents that the same may swing from a ceiling or other support freely.

Fig. 3 represents the threaded collar *b*, which is secured to the socket cover, as extending upwardly within the socket cover, while Fig. 4 represents this collar as reversed, in other words, extending downwardly, but my invention is not limited by the position of the threaded cover, as the same may occupy either position desired, according to the shade or glassware and the results to be obtained.

In connecting up the parts, as illustrated in Fig. 2, the electric conductors, connected to the socket, are to be passed through the aperture in the smaller end of the cover. The rim of the shade or glassware is to be 90 passed inside the circular edge of the cover and then the threaded sleeve *c* is passed inside the shade or glassware and connected with the threaded collar so that the shade or glassware is held all around the rim with 95 an even, firm but not tight bearing.

Where the device of my invention is connected to an electrolier or a bracket, it may occupy the inclined position shown in Fig. 1 or it may hang directly down or extend 100 directly upward, as the same is adapted substantially to any position. Where the socket cover is connected, as in Figs. 1 and 3, the pipe of a bracket or electrolier may extend through the aperture in the smaller 105 end of the cover, and the cover at this end may come up against a bead or other stop, as shown, and a clamping screw may pass

through the stop, or a nut on the inside of the cover upon this pipe may be employed, all of which fastening devices it is possible to use with the device of my invention. In 5 such instance, a socket is connected to the free end of said pipe, the electric conductors passing through the pipe.

The device of my invention is particularly applicable to keyless sockets, as so many electrical devices are employed nowadays where the light is operated by a switch rather than at the lamp sockets, and this is often necessary because of the height to which the lights are placed or the number of lights 10 grouped on a circuit.

In the device of my invention, the unstable shade ring is entirely done away with, as are also the plurality of spaced attaching screws which are so liable to injure the shade 20 or glassware, and in the device of my invention, the shade or glassware is held at the rim by an even, gentle all-around bearing which readily permits of the expansion and contraction of the shade or glassware 25 without liability of cracking the same.

I claim as my invention:

1. A combined socket cover and shade holder for electric light devices, comprising a conoidal socket cover apertured at the 30 smaller end for support, an enlarged lower portion of the same to receive a shade, a supporting member connected thereto, and means removably connected with the said member in an adjustable relation, for securing the shade or glassware in position.

2. A combined socket cover and shade holder for electric light devices, comprising a conoidal socket cover apertured at the smaller end for support, an enlarged lower portion of the same to receive a shade, a threaded collar connected internally to the socket cover at the larger lower portion in a permanent relation, and a threaded sleeve adapted for removable connection with the threaded collar and having a rim, the said sleeve coming inside of the shade or glassware and the rim of the shade fitting within the larger lower end of the socket cover. 40 45

3. A combined socket cover and shade holder for electric light devices, comprising a sheet metal socket cover of conoidal form apertured at the smaller end for connection with a means of support, and at the larger lower portion provided with an edge circular in cross section and adapted to receive a shade, a threaded flanged collar received concentrically with the larger lower end of the socket cover and at its flange securely fastened thereto, and a threaded sleeve adapted to be connected in an adjustable relation to the threaded collar, and said sleeve having a flange which, with the circular edge of the socket cover receives between them the rim of the shade or glassware and securely and adjustably holds the same. 50 55 60 65

Signed by me this 19th day of April, 1912.
LAURITZ W. ANDERSEN.
